US0D1035698S

(12) **United States Design Patent** (10) **Patent No.:** **US D1,035,698 S**
(45) **Date of Patent:** **** Jul. 16, 2024**

(54) **DISPLAY SCREEN OR PORTION THEREOF WITH A GRAPHICAL USER INTERFACE**

3,642,287 A 2/1972 Lally et al.
3,735,987 A 5/1973 Ohki
4,695,053 A 9/1987 Vazquez et al.
5,152,529 A 10/1992 Okada
5,188,363 A 2/1993 Marnell et al.

(71) Applicant: **IGT**, Las Vegas, NV (US)

(72) Inventors: **Bradford Brown**, Sparks, NV (US);
David Howe, Reno, NV (US)

(Continued)

(73) Assignee: **IGT**, Las Vegas, NV (US)

(**) Term: **15 Years**

(21) Appl. No.: **29/899,015**

(22) Filed: **Aug. 3, 2023**

Related U.S. Application Data

(60) Division of application No. 29/797,601, filed on Jul. 1, 2021, now Pat. No. Des. 998,627, which is a continuation of application No. 16/052,240, filed on Aug. 1, 2018, now Pat. No. 11,074,776, which is a continuation of application No. 15/273,119, filed on Sep. 22, 2016, now Pat. No. 10,049,526.

CLAIM

The ornamental design for a display screen or portion thereof with a graphical user interface, as shown and described herein.

DESCRIPTION

The FIGURE is a front view of a display screen or portion thereof with a graphical user interface of our new design. The dashed broken line perimeter in the drawing illustrates a display screen or portion thereof and forms no part of the claimed design. The remaining dashed broken lines in the drawing illustrate portions of the graphical user interface that form no part of the claimed design.
